United States Patent Office.

ALONZO W. CRAM, OF ST. LOUIS, MISSOURI.

Letters Patent No. 85,910, dated January 19, 1869.

IMPROVED CONDENSER FOR SPIRITS, STEAM, AND OTHER VAPORS.

The Schedule referred to in these Letters Patent and making part of the same.

To all whom it may concern:

Be it known that I, ALONZO W. CRAM, of the city and county of St. Louis, and State of Missouri, have invented a new and useful Improvement in Vapor and Gas-Condenser.

By the use of my condenser, steam-engines can be used to a greater advantage on the plains, and all through the country, where water is scarce, or bad for steam-purposes; and for distilling-purposes it is invaluable, as it can be run with small power.

By this process the steam is condensed, and the same condensed matter is pumped back into the boiler, and, in this way, saves all the water or other material used, and the boiler can always be supplied with good material to generate steam.

I do hereby declare that the following is a full and exact description of the same, reference being had to the annexed drawings, and letters marked thereon, the figures representing my vapor and gas-condenser, which consists of hollow arms, marked F, and being in a framework, so that it may be made to revolve.

O O O are fans, so constructed as to suck in the air as the machine revolves. These are made fast along the edges of the respective arms F on one side, with the other side flaring out, so as to catch the air as it revolves. They are also fastened at the top to the band B.

A is a band-wheel, made fast to the pipe supplying

the vapor to be condensed, which also acts as its journal, and which passes into the four arms F.

These open into a receiver, E, which is cup-shape, and provided with a pipe, H. As the receiver E revolves, the pipe H is so constructed with elbows, making the opening of said pipe to face and receive the condensed matter as it revolves with the receiver E.

Now the whole machine is set in motion by the band passing around the wheel A, or in any other way, and the vapor or gas is let into the top of the journal, and passes down to the arms F, where it comes in contact with the cool surfaces made so by the revolving of the machine, producing a cold current, and, after being condensed, passes out into the receiver E, whence it passes into pipe H, which is stationary, and forms a journal for E, and is conducted out of the machine to any desired place.

Now, what I claim, and for which I ask Letters Patent of the United States to be granted me, is—

The combination of the wheel A, the fans O O C, and the receiver E, the arms F, the pipe H, and the way of cooling the vapor, as above described, and for condensing vapors and gases, and for heating-purposes.

A. W. CRAM.
